E. ROGERS.
RAIL FASTENING FOR CONCRETE TIES.
APPLICATION FILED JAN. 24, 1921.

1,388,972.

Patented Aug. 30, 1921.

Inventor:
Edwin Rogers,
By Cheever & Cox
Atty.

UNITED STATES PATENT OFFICE.

EDWIN ROGERS, OF AURORA, ILLINOIS.

RAIL-FASTENING FOR CONCRETE TIES.

1,388,972.

Specification of Letters Patent. Patented Aug. 30, 1921.

Application filed January 24, 1921. Serial No. 439,425.

To all whom it may concern:

Be it known that I, EDWIN ROGERS, a citizen of the United States, residing at Aurora, in the county of Kane and State of Illinois, 5 have invented a certain new and useful Improvement in Rail-Fastenings for Concrete Ties, of which the following is a specification.

This invention relates to railroad track 10 equipment, particularly that in which concrete ties are used for supporting metallic rails—one form for such tie being shown in my prior Patent No. 1,204,904, dated November 14, 1916 and another improved form 15 of fastening for the rail and tie being shown in my Patent No. 1,358,468, dated November 9, 1920 on which later patent this device is more or less of an improvement.

The object of this invention is to provide 20 a comparatively simple, yet positive, mechanism for positioning the rail upon the ties and more particularly to provide improved means for supporting and bracing the tie in the ground whereby part of the strain 25 which ordinarily passes through the tie directly to the ground is transmitted through a wider area with resulting assurance that the pressure will not partially or wholly destroy the tie. In other words, 30 the primary object is to equalize the weight transmitted from the rail through the tie into the ground so that it is spread over a wide area as it enters the ground.

The invention consists in means for carrying 35 out the foregoing objects, which can be easily and cheaply made, which is satisfactory in use and is not readily liable to get out of order. More particularly the invention consists in details and features of construction hereafter more fully set forth in 40 the specification and claims.

Referring to the drawings in which similar numerals represent the same parts throughout the several views:

45 Figure 1 is a side view of a railroad rail and a transverse view of the tie on which it rests showing the mechanism of this invention combined therewith.

Fig. 2 is a sectional view through the rail 50 on the line 2—2 of Fig. 1.

Fig. 3 is a sectional detail view on the line 3—3 of Fig. 1.

Fig. 4 is a sectional detail view on the line 4 of Fig. 1.

55 In carrying out this invention a plurality of ties 10, preferably of the type shown in

said first mentioned patent are placed along the ground and over them are laid the rails 12 in suitable position for sustaining the passing trains. Each rail is secured to each 60 adjacent tie by the preferred form of mechanism of this invention shown in the drawing and to be now described.

In the same vertical plane with each rail and below it is an angle iron 14, shaped as 65 shown in the drawing so that it passes under the bottom of the adjacent tie, then upward in angular lines as shown and finally contacts the bottom of the rail in horizontal portions 16. Each of these last mentioned 70 portions is secured to the rail flange by a detachable clamping jaw 18, suitably secured in place by a detachable bolt 20 as clearly appears in Fig. 2. At the points where the angle iron turns the lower corners 24 of the tie 75 these angle irons are perforated to allow for the passage of U-shaped rods 26, having the bottom portions of the U form passing through the angle irons as shown in Fig. 3 and thence up to and through a plate 28 on 80 which the rail rests. The upper ends of these members 26 are suitably secured above this plate and the adjacent rail flange by any suitable means, as for instance, the washer nut mechanism 30. In order to carry 85 the load which is transmitted from the rail 12 down these members 26 and down the angle irons 14 to the ground without all of it passing through the tie 10, the rods 26 have pivoted to them below the angle irons, link 90 connections 32, located one on each side of the angle iron and entering an upright post 34 whose lower end is embedded in a concrete foundation 36 placed in the ground at one side or the other, as the case may be, of 95 the adjacent tie. The result of this construction is that the load coming down through the tie and the connecting parts 14—24 described exerts a pull on these members 32 which is resisted by the members 34—36 in the obvious manner, whereby part 100 of a load is transmitted into the ground through the members 36, while part of it is carried to the ground directly by the tie 10. Being divided in this way the load is not 105 sufficient at any one point to cause injury to any of the parts.

The parts described are so rigidly secured to the rail that it cannot creep in either direction—this largely because the upward 110 inclined portions of the angle irons 14 brace the portions of the rail between the ties and

prevent their sagging as the car wheels pass over them which sagging of these intervening portions is well understood to be one of the main causes of rail creeping.

5 Having thus described my invention, what I claim as new and desire to secure by Letters Patent, is:

- 10 1. In combination with a railroad rail and a tie therefor, a securing member attached to the rail at some distance on opposite sides of the tie, thence extending angularly downward to and below the tie, U-shaped sustaining rods located immediately adjacent to the sides of the tie passing through the first mentioned securing member, thence directly upward to the rail, means for securing these rods to the rail flanges, foundations set in the ground in which the device normally rests at points on opposite sides of the tie and upwardly inclined link connections between these foundation devices and the points of connection between the first two mentioned members.
- 15 2. In combination with a railroad rail and a tie therefor, a securing member attached to the rail at some distance on opposite sides

of the tie, thence extending angularly downward to and below the tie, U-shaped sustaining rods located immediately adjacent to the sides of the tie passing through the 25 first mentioned securing member, thence directly upward to the rail, means for securing these rods to the rail flanges, foundations set in the ground in which the device normally rests at points on opposite sides 30 of the tie and upwardly inclined link connections between these foundation devices and the points of connection between the first two mentioned members.

In witness whereof, I have hereunto subscribed my name in the presence of two witnesses.

EDWIN ROGERS.
